UNITED STATES PATENT OFFICE.

SAM H. LIBBY, OF EAST ORANGE, NEW JERSEY, ASSIGNOR TO SPRAGUE ELECTRIC COMPANY,
A CORPORATION OF NEW JERSEY.

AUTOMATIC CARRIER SYSTEM.

No. 904,788.

Specification of Letters Patent.

Patented Nov. 24, 1908.

Application filed March 12, 1906. Serial No. 305,439.

To all whom it may concern:

Be it known that I, SAM H. LIBBY, a citizen of the United States, residing at East Orange, county of Essex, State of New Jersey, have invented certain new and useful Improvements in Automatic Carrier Systems, of which the following is a specification.

The present invention relates to systems 10 wherein a carrier is adapted to be set in operation at one station, as, for example, at a loading station, and thereafter travel to another station, such as a dumping station, where it is automatically reversed and brought back to the first station at which it finally comes to rest, and has for its object to provide a simple and novel arrangement for automatically controlling the carrier.

To the above end the present invention 20 consists in the construction and arrangement of parts to be hereinafter described and particularly pointed out in the claims.

The present invention will be more fully understood and its objects and advantages 25 will more clearly appear from the following description taken in connection with the accompanying drawings, wherein

Figure 1 illustrates diagrammatically the motor and control mechanism of a carrier 30 together with the system of current distribution between the source of current supply and a number of stations, all arranged in accordance with one embodiment of the present invention; and Figs. 2 to 5 are similar 35 views of modifications having parts omitted therefrom, including the parts mounted upon the carrier, with the exception of the current collectors.

Reference being had to Fig. 1, A indicates 40 a motor for moving a carrier along its track; B indicates a hoisting motor mounted on the carrier; C is a reversing switch associated with the motor A; D is a controller for the hoisting motor; E is a limit switch of the 45 usual type adapted to open the circuit of the hoisting motor and operate the reversing switch of the traverse motor so as to stop the hoisting motor after the load has been raised and set the traverse motor in operation to 50 move the carrier to the dumping station; L and L¹ indicate a source of current supply from which current is taken to operate the motors; R¹, R² and R³ are resistance sections normally in the connection between the line

L and line l, which is one of the trolley 55 wires.

The carrier is provided with a current collector F adapted to engage with a supply conductor l² which may be connected to or form a continuation of the main conductor 60 L¹. In addition, current collectors F¹ and F² are adapted to engage the supply conductor l.

F³ is a contact device electrically connected with the current collector F and adapted 65 to coöperate with a conductor l² running parallel with the supply conductors l and l². The supply conductor l¹ is made continuous throughout the entire distance over which the carrier is adapted to travel, while the 70 supply conductors l, on the other hand, is made in sections 1, 2 and 3, separated from each other by insulated sections 4 and 5; the sections 4 and 5 being adjacent the dumping stations and the sections 1, 2 and 3 extending 75 between the stations. The sections 1, 2 and 3 are permanently connected to line L through a conductor 13, while the sections 4 and 5 may be connected to the same conductor by means of the switches S¹ and S². 80 When the switch S¹ is closed, the section 4 is energized, so that the circuit is not interrupted at the first dumping station and the car is therefore free to pass this station without being stopped. If switch S² is also 85 closed, section 5 is energized and the car is free to pass to a succeeding dumping station. If either of the switches S¹ or S² is left open, the section controlled thereby will remain 90 dead and the car will stop when it enters upon that section. At the loading station there is an additional dead section 6.

The arrangement illustrated is adapted for a system having one loading station and two dumping stations, but it will be seen that 95 the same principle may be employed for a system wherein there are any desired number of dumping stations. The conductor l² is dead throughout its length and is provided at each of the stations, either dumping or 100 loading, with short sections 7, 8 and 9, insulated from each other and from the rest of the conductors. The sections 7, 8 and 9 are connected in parallel to a series of conductors, 7^a, 8^a and 9^a, extending throughout the 105 length of the line. The conductors 7^a, 8^a and 9^a are in turn connected to line L through coils 7^b, 8^b and 9^b which respectively actuate

switches 10, 11 and 12, controlling the resistance sections R^1 , R^2 , R^3 .

G is a relay having its actuating coil arranged in the connection between line L and supply conductor l.

Assuming that the parts are in the positions illustrated, current will flow from line L^1 , through the field coil a of the traverse motor, through contacts c^1 , c and c^2 of the reversing switch, through the armature a^1 of the traverse motor, and thence through contacts c^3 , c^4 and c^5 of the reversing switch, to current collector F^1 , line l, through the actuating coil of relay G, through resistance R^3 , R^2 and R^1 to line L. The traverse motor will now begin to operate and the carrier will move toward the left at a slow rate of speed by reason of the resistance in the supply circuit. When the contact device F^3 comes into engagement with section 7 of the auxiliary conductor l^2 , current flows from line L^1 , through this contact device and section 7, and thence through the coil 7^b to line L. Coil 7^b , being energized, closes switch 10 and short-circuits resistance section R^1 , thus causing the current to the motor to be increased and the carrier to move at a higher rate of speed. The switch 10 is prevented from opening again when the contact F^3 leaves section 7, by reason of a maintaining circuit which passes from line L^1 , through contacts g of the relay G, and thence through the auxiliary contacts 14 associated with switch 10 and through the coil 7^b to line L. When the carrier reaches section 8, current is supplied to coil 8^b in the same manner as was previously done in the case of coil 7^b , and switch 11 closes and cuts out additional resistance sections R^2 ; thereby still further increasing the speed of the carrier. Switch 11 is also maintained closed by means of a maintaining circuit passing through the contacts of the relay and through the auxiliary contacts 15 associated with the switch itself. When the section 9 is reached, switch 12 is closed and resistance section R^3 is eliminated, the motor now running at its highest speed. The carrier proceeds at this speed to the dumping station at which it is to be stopped. It is of course evident that the number of resistance steps is not confined to three, but may be anything desired.

If it is desired to stop the carrier at the first dumping station, the switch S^1 is left open, maintaining section 4 dead, and a stop 17 is adjusted in the path of the arm 18 which trips the reversing switch. When this dumping station is reached by the carrier, the current collector F^1 enters upon the dead section 4 and the motor is open-circuited. At the same time the circuit through the coil of the relay and the actuating coils of the resistance switches is interrupted and the relay drops and the resistance switches open. The breaking of the motor circuit de-

energizes the holding coil for the brake A^1 and the brake is applied, bringing the carrier to rest. In the meantime the load has been dumped in any suitable manner and the arm 18, striking against stop 17, is moved out of engagement with the shoulder on cam 19 secured to the shaft of the reverser cylinder, permitting the spring 20 to throw the reverser into the opposite running position from that shown. Current collector F^2 still remains in contact with section 1 and this collector, which has heretofore been idle, now becomes active and collector F^1 becomes inoperative. A circuit may now be traced from line L^1 , through field coil of the traverse motor, through contacts c^1 , c^6 , c^7 and c^8 , through the armature of the traverse motor, reverser contacts c^2 , c^8 , c^9 and c^{10} , to current collector F^2 , and thence through section 1, through actuating coil of relay G, and thence through resistance sections R^5 , R^2 and R^1 to line L. It will be seen that the motor is now connected for operation in the reverse direction and the carrier proceeds slowly toward the loading station. When section 7, at the dumping station, is reached, current will be supplied to this section from the contact device F^3 and will flow through conductor 7^a and thence through coil 7^b to line L, causing the switch 10 to close and resistance R^1 to be cut out. In the same way, as sections 8 and 9 adjacent the dumping station are reached, coils 8^b and 9^b are energized, causing the resistance sections R^2 and R^3 to be cut out. The resistance switches are maintained closed through the maintaining circuit, as before. The elimination of the several resistance sections causes the motor to speed up and the carrier to travel toward the loading station at full speed. When the loading station is reached the current collector F^2 runs onto the dead section 6 and the motor circuit is again interrupted and the brake applied to bring the carrier to rest. Also, the circuit through the relay coil and the actuating coils for the resistance switches is interrupted and the resistance is cut in, leaving the system in condition to start the motor again upon a low current. When the reversing switch is again operated to the position indicated, the carrier is started toward the dumping stations in the manner previously described.

It is evident that if it is desired to dump at the second dumping station the switch S^1 is closed and stop 17 is placed in operative position, while stop 17 is maintained out of the path of movement of the arm 18. Therefore when section 4 is reached the circuits are not interrupted and the carrier is free to continue to the next dumping station, at which point the circuits will be interrupted at section 5 and the carrier will be reversed and returned to the loading station in the same manner as before.

In Fig. 2 I have illustrated a somewhat simpler arrangement wherein a single resistance section R is adapted to be included in the supply circuit in starting the motor and 5 to be cut out after the carrier has moved a predetermined distance. L and L' indicate the source of current supply, as before, and 7 and $7'$ the supply conductors from which the current-collecting devices F , F^1 and F^2 10 take current. No auxiliary trolley wires are employed but the supply conductor $7'$, in addition to the sections corresponding to the several sections of the same supply conductor in Fig. 1, is provided with additional 15 short sections 21 and 22, arranged, respectively, at the loading and dumping stations and insulated from the rest of the conductor. Normally, conductor l is connected to supply main L through the contacts h of 20 the relay H and resistance R . Sections 21 and 22, which are in electrical communication with each other, are connected to supply main L , through the actuating coil h^1 of the relay H , and resistance R . In starting, current flows from conductor $7'$, through 25 collector F , through the motor, through collector F^1 , section 21, coil h^1 , resistance R , to line L ; the motor starting with the resistance in circuit and the core of the relay 30 being lifted. The resistance remains in circuit as long as current-collector F^1 remains on section 21, but as soon as it passes into engagement with section 1 a new circuit is 35 established from this current-collector through the contacts h^2 of the relay, maintaining coil h^3 of the relay and thence directly to line L . Thus the resistance R is cut out and the motor travels at full speed until section 22 of one of the dumping 40 stations is reached. At this point the resistance is cut in again and the carriage is slowed down so that when the carrier enters upon the dead section the motor is stopped and 45 reversed as previously described, without undue strain upon the apparatus. The maintaining circuit for the relay is opened at the same time and the relay drops, so that in starting on its return journey the carrier is supplied with current which flows 50 through section 22 and thence through coil h^1 , and resistance R , to line L , as in starting from the loading station; the resistance being again cut out when the current-collector F^2 leaves section 22 and enters upon section 55 1. The purpose of the contacts h and the relay is to permit the carrier to receive current in case the current-collectors leave the trolley wires while on section 1. This of course will cause the relay to drop, so that 60 when the current-collectors are again brought into engagement with the trolley wires, current flows from section 1, through the contacts h of the relay, and thence through resistance R to line L ; the carrier 65 being enabled to complete its journey to the

station at the low speed. The modification shown in Fig. 2 may be employed to advantage for heavy service, since it enables the carrier to be gradually slowed down prior to being stopped and reversed. 70

In Fig. 3, two supply conductors l and l' , together with independent conductor sections 23 and 24 at the loading and dumping stations, respectively, are employed. Section 1 is normally connected to line L 75 through resistance section R^4 and coil i of relay I . Only three current-collectors, F , F^1 and F^2 , are required, although an additional one, F^4 , may be provided for co-operation with the sections 23 and 24. If the collector F^4 is dispensed with, the sections 23 and 24 may be arranged in close proximity to the conductor l' so as to be engaged by collector F . In starting from either station, current is supplied from line l' , to collector F , and 80 thence passes through the motor and the current-collector F^1 or F^2 to trolley wire l , and from trolley wire l the current passes through resistance R^4 , coil of the relay I , to line L . Thus the resistance is included in the 85 motor circuit. The parts are so proportioned that the current now passing through the coil of the relay is insufficient to operate the relay. When, however, current-collector F or F^4 , as the case may be, engages with 90 either section 23 or 24, dependent upon whether the carrier is moving from the loading or from the dumping station, current passes directly from line L' , through resistance r , coil of the relay I , to line L ; the resistance r being so proportioned that the 95 current now is of sufficient strength to operate the relay to close the contacts i , thereby cutting out resistance R^4 . When the current-collector leaves the auxiliary section, 100 the relay is maintained closed by the motor current. 105

The modification shown in Fig. 4 is somewhat similar to that of Fig. 1, except that the controlling relay is omitted. L and L' 110 are the source of current supply, l and l' are the trolley wires or supply conductors. The auxiliary conductor l^2 corresponds in all respects to conductor l^2 of Fig. 1, and there is an additional conductor l^3 . Conductor l^3 is 115 sectionalized in exactly the same manner as conductor l^2 . In addition to the main current collectors F , F^1 and F^2 , two additional collectors F^3 , F^4 are provided. Three resistance sections R^1 , R^2 and R^3 are controlled 120 by switches 10, 11 and 12, and these switches are controlled respectively by electromagnets 7^e , 8^e and 9^e . Starting from the loading station, current flows from line l' , through collector F , through the motor, through collector F^1 , section 1 of trolley l , resistances R^3 , R^2 and R^1 to line L . When current-collector F^3 engages section 7 of the auxiliary conductor l^2 , current flows from line L' , 125 through collectors F and F^3 , section 7, 130

through actuating coil of the electromagnet 7^c, to line L. This causes switch 10 to be closed and resistance section R¹ to be removed from the circuit. As soon as the switch 10 closes, it establishes a maintaining circuit for itself from line L¹, collectors F and F^c, auxiliary contacts 25 associated with the switch 10, thence through the actuating coil of the electromagnet 7^a, to line L. Therefore the switch 10 is maintained closed after the carrier passes beyond section 7. In the same way, switches 11 and 12 are closed and held closed by means of the maintaining circuits established through the auxiliary contacts 26 and 27 associated therewith. In returning from the dumping station, the operation of cutting out the resistance is repeated as the carrier passes the sections 7, 8 and 9 at the dumping station.

In Fig. 5 a further modification is illustrated wherein it is necessary to have only one conductor extending throughout the system for properly connecting the sections corresponding to sections 7, 8 and 9 in the previous figures to the resistance controlling apparatus. L, L¹, l, l¹, l² and l³ in this figure and in Fig. 4 indicate corresponding parts, except that only two auxiliary sections 7 and 8 are required adjacent each station in the conductor l². Similarly, current collectors F, F¹, F², F^a and F^c correspond to the current-collectors in Fig. 4 having similar reference characters. Resistance sections R¹, R² and R³ are controlled by switches 10, 11 and 12, and the switches are actuated by electromagnets 7^a, 8^a and 9^a. The electromagnets are controlled by a relay K. In starting, current flows from line L¹, to collector F, through the motor, through collector F^c, section 1 of trolley wire l, resistance sections R¹, R² and R³, to line L. When collector F^c engages section 7 of the auxiliary conductor l², current flows from line L¹, through collectors F and F^c, through section 7, wire 28, which connects all of the sections 7 and 8 throughout the system together, through the actuating coil k of the relay, and thence to line L. The energizing of the relay causes it to close its contacts k^a, and the circuit may now be traced from line L¹, through collector F and F^c, auxiliary conductor l², through the actuating coil of the electromagnet 7^a, through the contacts k^a of the relay, through the interlocking contacts 29 and 30 associated with switches 11 and 12, respectively, to line L. The electromagnet 7^a being thus energized, closes switch 10 and cuts out resistance section R¹. As soon as the switch 10 closes, it establishes a maintaining circuit for its actuating electromagnet through auxiliary contacts 31, so that current, after passing through the coil of the electromagnet, flows through the contacts 31 and then directly to line L, independently of the relay and the remaining

switches. When the carrier leaves section 7, the circuit containing the coil of the relay is interrupted and the relay drops. As soon as the relay drops, a circuit may be traced from auxiliary conductor l², through the 7^a coil of electromagnet 8^a, through auxiliary contacts 32 associated with switch 10, through contact k^a in the relay, and thence through contacts 30 associated with switch 12, to line L. Electromagnet 8^a, being thus energized, closes switch 11 and cuts out resistance R², at the same time establishing a maintaining circuit for itself to line L directly through auxiliary contacts 33 associated therewith.

80

In order to obtain the proper time interval between the closing of switches 10 and 11, the relay may be made slow acting, or the sections 7 may be made of considerable length so that the relay, after being once opened, cannot immediately close again. When section 8 is reached, the relay is again lifted and current passes from conductor l² through the coil of electromagnet 9^a, through auxiliary contacts 34 associated with switch 11, through contacts k^a on the relay, to line L. The switch 12 is therefore closed and is held closed by a maintaining circuit which it establishes through auxiliary contacts 35 connected with this switch. As the carrier passes on, the relay is again deenergized, but all the switches are maintained closed until the dead section at the dumping station is reached, whereupon all the circuits will be interrupted and the carrier will be caused to start on its return trip with all resistance in circuit, which resistance will thereafter be automatically cut out again in the manner just described.

95

For the sake of clearness many of the connections, whereby there may be any number of stations at any one of which the carrier may be automatically stopped and reversed, have been omitted from the last four figures. These connections may, however, be the same as those for accomplishing this same purpose in Fig. 1, or other suitable arrangements may be employed if desired.

110

It will now be seen that the present invention provides simple and effective means whereby a carrier may be set in operation and automatically accelerated, thereafter being reversed and again accelerated, and finally returned to the starting point without requiring the attention of the operator or making it possible to apply too heavy currents to the motor in starting, as often happens where the acceleration is controlled by the operator.

115

In the foregoing description and in the drawings I have disclosed preferred embodiments of my invention, but it will of course be understood that in its broader aspects the invention may be otherwise carried out than in these specific forms so disclosed,

120

130

and in the appended claims I intend to cover all such modifications in addition to the modification illustrated.

What I claim as new and desire to secure 5 by Letters Patent of the United States, is,--

1. In an electrically-operated carrier system, a source of current supply, a circuit connected to said source, a resistance normally in said circuit and located at a fixed 10 point, a carrier receiving current from said circuit, and means automatically controlled by said carrier for eliminating said resistance.
2. In an electrically-operated carrier system, a source of current supply, a circuit connected to said source, a resistance normally in said circuit and located at a fixed 15 point, a switch for eliminating said resistance, a carrier receiving current from said circuit, and means controlled by said carrier for operating said switch.
3. In an electrically-operated carrier system, a source of current supply, a circuit connected to said source, a resistance normally in said circuit and located at a fixed 20 point, a switch for controlling said resistance, electro-magnetic actuating means for said switch, a carrier receiving current from said circuit, and means associated with said 25 carrier for completing a circuit through said actuating means.
4. In an electrically-operated carrier system, a source of current supply, a circuit connected to said source, a resistance normally in said circuit and located at a fixed 30 point, a traveling carrier receiving current from said circuit, and means automatically controlled by said carrier for eliminating said resistance when the carrier reaches a 35 predetermined point in its travel.
5. In an electrically-operated carrier system, a source of current supply, a circuit connected to said source, a resistance normally in said circuit and located at a fixed 40 point, a switch for eliminating said resistance, a traveling carrier receiving current from said circuit, and means automatically controlled by said carrier for operating said switch when the carrier reaches a predetermined point in its travel.
6. In an electrically-operated carrier system, a source of current supply, a circuit connected to said source, a resistance in said circuit, a switch for controlling said resistance, actuating means for said switch, a controlling circuit for said actuating means, a carrier receiving current from said first mentioned circuit, and means associated with said carrier for completing said control circuit when the carrier reaches a predetermined point in its travel.
7. In an electrically-operated carrier system, a source of current supply, a circuit connected to said source, resistance in the said 60 circuit, a circuit controlling and resistance 65 regulating device in said circuit, a control circuit for said controlling and regulating device, a traveling carrier receiving current from said supply circuit, a contact in said control circuit adjacent the path of movement of the carrier, and a contact on said carrier adapted to co-operate with said first contact to complete said control circuit.
8. In an electrically-operated carrier system, a source of current supply, a circuit connected to said source, resistance normally in said circuit and located at a fixed point, a traveling carrier receiving current from said circuit, and means automatically controlled by said carrier for eliminating said resistance when the carrier reaches a predetermined point in its travel.
9. In an electrically-operated carrier system, a source of current supply, a circuit connected to said source, resistance normally in said circuit and located at a fixed point, a traveling carrier receiving current from said circuit, and means automatically controlled by said carrier for gradually eliminating said resistance during the travel of the carrier.
10. In an electrically-operated carrier system, a source of current supply, a circuit connected to said source, resistance normally in said circuit and located at a fixed point, a carrier receiving current from said circuit, and means automatically controlled by said carrier for eliminating said resistance step-by-step.
11. In an electrically-operated carrier system, a source of current supply, a circuit connected to said source, resistance normally in said circuit and located at a fixed point, a traveling carrier receiving current from said circuit, and means automatically controlled by said carrier for eliminating said resistance step-by-step as the carrier reaches predetermined points in its travel.
12. In an electrically-operated carrier system, a source of current supply, a circuit connected to said source, a resistance normally in said circuit and located at a fixed point, a traveling carrier receiving current from said circuit, a loading station and a dumping station, and means automatically controlled by said carrier for eliminating said resistance from said circuit after the carrier has moved a predetermined distance from either station toward the other.
13. In an electrically-operated carrier system, a source of current supply, a circuit connected to said source, resistance normally in said circuit and located at a fixed point, a loading and an unloading station, a carrier receiving current from said circuit and adapted to travel between said stations, and means automatically controlled by said carrier for eliminating said resistance step-by-step as the carrier moves from either station toward the other.

14. In an electrically-operated carrier system, a source of current supply, a circuit connected to said source, a resistance in said circuit, a loading station and an unloading station, a carrier receiving current from said circuit and adapted to travel between said stations, a switch for controlling said resistances, electromagnetic actuating means for said switch, and means for energizing said actuating means when the carrier has moved a predetermined distance from either station toward the other. 70
15. In an electrically-operated carrier system, a source of current supply, a circuit connected to said source, a resistance in said circuit, a resistance-controlling switch, a switch-controlling circuit, a plurality of stations, a carrier receiving current from said circuit and adapted to travel between said stations, and means comprising co-operating devices on said carrier and at each of said stations for controlling the switch-controlling circuit. 75
16. In an electrically-operated carrier system, a source of current supply, a circuit connected to said source, a resistance in said circuit, a switch for eliminating said resistance, a switch-controlling circuit, a plurality of stations, a carrier receiving current from said circuit and adapted to travel between said stations, a contact adjacent each of said stations arranged in said switch-controlling circuit, and a co-operating contact mounted on said carrier. 80
17. In an electrically-operated carrier system, a supply circuit, resistance in said circuit, a plurality of switches controlling said resistance, a traveling carrier receiving current from said circuit, and means controlled by said carrier for operating said switches in automatic progression during the travel of the carrier. 85
18. In an electrically-operated carrier system, a supply circuit, resistance in said supply circuit, a plurality of switches controlling said resistance, a traveling carrier receiving current from said circuit and means controlled by the carrier for operating said switches in automatic succession during a predetermined movement of said carrier. 90
19. In an electrically-operated carrier system, a supply circuit, resistance in said circuit, switches for controlling said resistance, a plurality of stations, a carrier receiving current from said circuit and adapted to travel between said stations, and means for causing said switches to operate in automatic succession as the carrier moves from either station toward the other. 100
20. In an electrically-operated carrier system, a loading station and unloading station, supply conductors joining stations, a traveling carrier receiving current from said conductors, means at one of said stations co- operating with means on the carrier for automatically reversing the carrier, and means automatically operated by said carrier varying the difference of potential between said supply conductors as the carrier moves from either station toward the other. 105
21. In a traveling carrier system, a source of current-supply, a circuit including a main conductor connected to said source, a resistance in said circuit, a carrier adapted to receive current from said main conductor, an electromagnetically-operated switch for eliminating said resistance from said circuit, a contact in the path of movement of the carrier for controlling the actuating circuit for said switch, and a maintaining circuit for said switch. 110
22. In a traveling carrier system, a source of current supply, a circuit including a main conductor connected to said source, a resistance in said circuit, a carrier adapted to receive current from said main conductor, an electromagnetically-operated switch for eliminating said resistance from said circuit, a contact in the path of movement of the carrier for controlling the actuating circuit for said switch, and auxiliary contacts associated with said switch for completing a maintaining circuit for said switch. 115
23. In a traveling carrier system, a source of current supply, a circuit including a main conductor connected to said source, a sectional resistance in said circuit, a carrier adapted to receive current from said main conductor, a plurality of electromagnetically-operated switches for eliminating said resistances, and contacts in the path of movement of the carrier adapted to control the actuating circuits for said switches. 120
24. In a traveling carrier system, a source of current supply, a circuit including a main conductor connected to said source, a sectional resistance in said circuit, a carrier adapted to receive current from said main conductor, a plurality of electromagnetically-operated switches for eliminating said resistances, contacts in the path of movement of the carrier adapted to control the actuating circuits for said switches, and means associated with said switches for completing maintaining circuits for the switches. 125
25. In a traveling carrier system, a source of current supply, a circuit including a main conductor connected to said source, a resistance in said circuit, a plurality of stations, a carrier adapted to travel between said stations and receiving current from said main conductor, an electromagnetically-controlled switch for eliminating said resistance from said circuit, and a contact near each of said stations for controlling the controlling-circuit for said switches, said contacts being in the path of movement of the carrier. 130

- of current supply, a circuit including a main conductor connected to said source, a resistance in said circuit, a plurality of stations, a carrier adapted to travel between said stations and receiving current from said main conductor, an electromagnetically-controlled switch for eliminating said resistance from said circuit, a contact near each of said stations for controlling the controlling-circuit for said switch, and an auxiliary trolley on said carrier for engaging said contacts. 55
27. In a traveling carrier system, a source of current supply, a circuit including a main conductor connected to said source, a resistance in said circuit, a switch for eliminating said resistance from said circuit, a controlling circuit for said switch, a traveling carrier having a main current collector adapted to receive current from said main conductor, a contact in the switch-controlling circuit, and an auxiliary current collector in electrical connection with the main current collector, said auxiliary collector being arranged to engage with the said contact in the switch-controlling circuit. 60
28. In a traveling carrier system, a source of current supply, a circuit including a main conductor connected to said source, a resistance in said circuit, a plurality of stations, a carrier adapted to travel between said stations, a main current-collector on said carrier adapted to engage said main conductor, an electromagnetically-actuated switch for eliminating said resistance from said circuit, a contact near each of said stations for controlling the actuating circuit of said switch, an auxiliary current collector on said carrier adapted to engage said contacts, and a maintaining circuit for said switch. 65
29. In a traveling carrier system, a source of current supply, a loading station and an unloading station, a resistance, a main conductor extending between said stations and connected to said source through said resistance, a dead section in said main conductor at said unloading station, an electromagnetically-actuated switch for cutting out said resistance, a carrier having a main current collector adapted to engage said main conductor, a contact adjacent each station and connected to the actuating circuit for said switch, an auxiliary current collector on said main carrier adapted to engage said contacts, a maintaining circuit for said switch in series with said main current collector, and co-operating members at the unloading station and upon the carrier for reversing the carrier when the main current collector enters upon the dead section. 70
31. In a traveling carrier system, a source of current supply, a loading station and a plurality of unloading stations, a main conductor comprising a main section between each two successive stations, and a dead section at each station, a connection between said main sections and said source including a resistance, means for connecting or disconnecting the dead sections at the unloading stations to the source, an electromagnetically-actuated switch for cutting out said resistance, a contact near each station for controlling the actuating circuit of said switch, a carrier adapted to travel between said stations, a main current collector engaging said main conductor, an auxiliary current collector adapted to engage said contacts, and a maintaining circuit for said switch in series with the main current collector. 75
- In witness whereof, I have hereunto set my hand this eighth day of March, 1906.
- SAM H. LIBBY.
- Witnesses:
- ROGER H. BUTTERWORTH,
ANNA M. GILLIN.
